Fig. 7

<img alt="Fig. 8: A cross-sectional diagram of a component with various labeled parts. The diagram shows a central vertical structure with a horizontal slot at the top. A vertical tube labeled '14' extends from the top. A horizontal tube labeled '15' is positioned above the slot. A vertical pipe labeled '19' is attached to the side. The central structure is labeled 'Insulation 32'. Various other parts are labeled with numbers: 10, 110, 102, 12, 22, 39, 44, 46, 48, 50, 52, 54, 56, 58, 60, 64, 74, 76, 78, 80, 88, 90, 92, 94, 96, 98, 100, 102, 104, 106, 108, 110, 112, 114, 116, 118, 120, 122, 124, 126, 128, 130, 132, 134, 136, 138, 140, 142, 144, 146, 148, 150, 152, 154, 156, 158, 160, 162, 164, 166, 168, 170, 172, 174, 176, 178, 180, 182, 184, 186, 188, 190, 192, 194, 196, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, 2077, 2078, 2079, 2079, 2080, 2081, 2082, 2083, 2084, 2085, 2086, 2087, 2088, 2089, 2089, 2090, 2091, 2092, 2093, 2094, 2095, 2096, 2097, 2098, 2099, 2099, 2100, 2101, 2102, 2103, 2104, 2105, 2106, 2107, 2108, 2109, 2109, 2110, 2111, 2112, 2113, 2114, 2115, 2116, 2117, 2118, 2119, 2119, 2120, 2121, 2122, 2123, 2124, 2125, 2126, 2127, 2128, 2129, 2129, 2130, 2131, 2132, 2133, 2134, 2135, 2136, 2137, 2138, 2139, 2139, 2140, 2141, 2142, 2143, 2144, 2145, 2146, 2147, 2148, 2149, 2149,

SWITCH

Calvin J. Werner, Dayton, Ohio, assignor, by
mesne assignments, to General Motors Cor-
poration, Detroit, Mich., a corporation of Dela-
ware

Application October 27, 1932, Serial No. 639,750

14 Claims. (Cl. 200—116)

This invention relates to a switch and more particularly to a switch for controlling an electrical circuit.

It is an object of this invention to provide a switch adapted for manual control and having means for automatically interrupting a circuit in response to abnormal current flow thru said circuit.

Another object of this invention is to provide a switch capable of manual operation that breaks the circuit with a snap action regardless of the speed of manual operation.

Another object of this invention is to provide a switch that may be manually operated and that may be automatically opened, and that whether automatically or manually opened, opens with a snap action.

Another object of this invention is to provide a switch embodying a thermostatic control assembly that is separable therefrom as a unit and changeable without altering the remainder of said switch.

Another object of this invention is to provide a switch having an adjustment for controlling the flexure of the thermostatic member that is necessary to permit the automatic operation of the switch.

Still another object of this invention is to provide a switch that is adaptable to a variety of uses, and which while having adjustments and changeable elements to fit such uses, still lends itself to convenience and ease of manufacture as well as low cost and ruggedness.

Further objects and advantages of the present invention will be apparent from the following description, reference being had to the accompanying drawings wherein a preferred embodiment of one form of the present invention is clearly shown.

In the drawings:

Fig. 1 is a perspective view of a switch embodying the present invention, and shows the contacts in the open or disengaged position.

Fig. 2 is also a perspective view of the switch, and shows the contacts in the closed or engaged position.

Fig. 3 is an elevation of the switch showing some of the details of construction.

Fig. 4 is also an elevation of the switch taken substantially as indicated by the arrows 4—4 in Fig. 3.

Fig. 5 is a sectional view of the switch taken substantially on the line in the direction of arrows 5—5 of Fig. 4.

Fig. 6 is a partially fragmentary sectional view

of the switch taken substantially on the line and in the direction of arrows 6—6 of Fig. 5.

Fig. 7 is a fragmentary sectional view taken substantially on the line 7—7 of Fig. 8, and showing a modification in some of the pivotally mounted parts of the switch.

Fig. 8 is an elevation showing the modification indicated in Fig. 7.

With particular reference to the drawings, brackets 10 and 12 are secured to a mounting 14 that is preferably made of insulating material. Angle members 13 and 15 are secured to the mounting 14 by rivets 17 and 19 respectively, or other suitable means and are for use in mounting the switch. The bracket 10 has a portion 16 that forms a support for a portion of the switch structure. A subassembly comprising a cam member 18, preferably made of insulating material, a lever arm 20 having angularly disposed extensions 22 and 24, and a link 26 is pivotally mounted to the portion 16 of bracket 10 on a pin or shaft 28. A sleeve 30 surrounds the mid-portion of the pin or shaft 28, and extends from the extension 24 through the extension 22 and the portion 16 of the bracket 10 to a pivotally mounted member 32 to which the pin or shaft 28 was secured. The sleeve 30 thus acts as a spacer and insures free rotary motion of the subassembly. The member 32 is pivotally mounted to the portion 16 of the bracket 10 by a rivet 34 or any suitable means. A screw 36 projects through an elongated aperture 38 in the pivotally mounted member 32 and is threaded into the portion 16 of the bracket 10 so that the member 32 may be pivotally moved about the rivet 34 when the screw 36 is loosened, and will be clamped or held in position when the screw 36 is tightened.

The member 40 having an angular extension 42 is slidably mounted on the lever arm 20 by means of rivets 44 and 46 having shoulder portions 52 and 54 respectively that are slidable in elongated apertures 48 and 50 in the member 40. The rivet 46 has an extension 56 to which springs or resilient members 58 and 60 are connected. The spring 58 is also connected to the bracket 10 through a lug 62 that is struck from the bracket. An operating lever 64 projects through an aperture 66 in the mounting 14 and through an aperture 68 in the angular extension 42 of the slidably mounted member 40. The end of the operating lever 64 that projects through the aperture 68 is connected to the spring 60, and the operating lever is provided with a shoulder 70 that is urged against the angular extension 42 by the spring 60. The pressure of the shoul-

der 70 against the extension 42 tends to slide the slidably mounted member 40 so that the shoulders 52 and 54 of the rivets 44 and 46 rest at the ends of the apertures 48 and 50, and an end 72 of the slidably mounted member 40 projects beyond the end of the lever arm 20. The spring 58 urges or biases the subassembly formed by the cam member 18, the lever arm 20 and the slidably mounted member 40 to rotate in one direction about their pivotal mounting formed by the pin or shaft 28.

The brackets 10 and 12 are preferably secured to the mounting 14 by screws 73 and 74 respectively threaded into angularly disposed portions of the brackets. The stationary contact carrying member 76 has a portion located intermediate the bracket 10 and mounting 14 so that it is held in place by the screw 73. A resilient contact carrying member 78 is secured to the mounting 14 preferably by means of a screw 80 and a cooperating nut 82. The contact carrying member 78 has a lug 84 formed on one end and projecting into an aperture 86 in the mounting 14 to prevent the member from turning. The contact carrying member 76 and the resilient contact carrying member 78 have cooperating contacts 88 and 90 respectively secured thereto. The resilient contact carrying member 78 is normally biased so as to urge the contacts 88 and 90 into engagement. Then, the resilient contact carrying member 78 extends to a position in cooperative relation with the cam member 18 so that movement of the cam in one direction causes it to engage the resilient contact carrying member 78 to force the contacts 88 and 90 apart or cause them to be disengaged.

A thermostatic latch assembly is secured to the brackets 10 and 12 by means of bolts 100 and 102 respectively which have cooperating nuts 104 and 106 respectively. The bolt 102 passes through the bracket 12 and the bracket 10 and is insulated from the bracket 10 by means of insulating washers 108 and 110. A nut 112 and washer 114 on the bolt 102 serve as spacers, and to hold the bolt in position when the latch assembly is removed. A stop member 116 is secured to the bracket 10 by the bolt 100, and washers 118 and 120 and a nut 122 on the bolt 100 serve as spacers and hold that bolt and the stop member 116 in position when the latch assembly is removed.

The thermostatic latch assembly includes a strip or block 124 of insulating and heat resisting material having an elongated opening 126 therein and apertures 128 and 130 therethrough for the accommodation of the bolts 100 and 102 respectively. The apertures 128 and 130 have sleeves 132 and 134 respectively therein which sleeves have rolled or riveted end portions to secure them in position. The opening 126 has a shoulder portion 136 formed therein at one end thereof to which a thermostatic member or bimetallic strip 138 is secured by a rivet 140 or other suitable means. An end portion 142 of the rivet 140 is set into a recess 144 in the block or strip 124 so that the rivet is totally within the confines of the block or strip 124. A coil of resistance wire or heating element 146 is space-wound on the block or strip 124 so that it is exposed to more than one side of the thermostatic member 138 and surrounds a portion of that member, and is spaced therefrom so as not to impede or restrain the flexure of the thermostatic member caused by heat. The ends of the coil 146 are electrically connected to the

bolts 100 and 102, and washers 148 and 150 are placed intermediate the nuts 104 and 106 respectively and the block or strip 124. The thermostatic member 138 has an angularly extending portion 152 that projects from the opening 126 to engage the extending portion 72 of the slidably mounted member 40 to latch or hold the pivotally mounted subassembly against the urging force of the resilient member 58 to permit the contacts to remain in the closed or engaged position while the subassembly is thus held.

A lug 154 located intermediate the head of the screw 80 and the mounting 14, and preferably having a screw 156 threaded therein forms one terminal for the switch and is connected to the contact 90 through the screw 80 and the contact carrying member 78. The contact carrying member 76 is electrically connected to the bracket 10 by virtue of its being held in position intermediate the bracket 10 and the mounting 14 by the screw 73. The bracket 10 is electrically connected to one end of the resistance coil or heating element 146 thru the bolt 100, and the other end of the coil 146 is connected to the bracket 12 through the bolt 102 which bolt is insulated from the bracket 10. A lug 158 located intermediate the head of the screw 74 and the mounting 14 and preferably having the screw 160 threaded therein forms the other terminal of the switch. Lock washers 162 and 164 are provided for the screws 80 and 74 respectively to prevent them from loosening. It may thus be seen that the brackets 10 and 12 form a part of the switch circuit, and that the resistance coil or heating element 146 is connected in series with the contacts so that the heat applied to the thermostatic member 152 is proportional to the current through the switch circuit.

With particular reference to Figs. 7 and 8, the parts bearing reference numerals to those previously used are similar and perform similar functions. However, in this modification apertures 170 and 172 are provided in the lever arm 20 and slidably mounted member 40 respectively. A lug 174 is formed at one end in the aperture 170, and a lug 176 is formed at one end of the aperture 172 so that the said lugs are oppositely disposed and adapted to hold a spring or resilient member 178 within the apertures. The spring or resilient member 178 then urges the slidably mounted member 40 in one direction so that the shoulder portions 52 and 54 of the rivets 44 and 46 respectively are disposed at the ends of their respective elongated apertures 52 and 54 respectively, and so that the end portion 72 of the slidably mounted member 40 projects beyond the end of the lever arm 20.

In the operation of the switch, assuming it in the off of contact disengaging position as shown in Fig. 1, it may be manually operated to engage the contacts by substantially linear movement of the operating member 64 so that the shoulder 70 is forced against the portion 42 of the slidably mounted member 40. The force thus applied rotates the pivotally mounted subassembly about the pivot formed by the pin or shaft 28, and causes the cam member 18 to rotate so as to permit the normal biasing of the resilient contact carrying member 78 to close the contacts or cause them to be engaged. The pivotally mounted subassembly is thus moved against the urging force of the spring or resilient member 58, away from the stop member 116. In movement, the end portion 72 of the slidably mounted member 40 engages the angu-

larly extending portion 152 of the thermostatic member 138 and causes it to flex until the end portion 72 passes the end of the thermostatic member 138 sufficiently to permit a latching engagement. The switch then assumes a position substantially as shown in Fig. 2.

Then, to open or disengage the contacts manually the operating member 64 is moved substantially linearly in a direction opposite to that for causing engagement of the contacts. When the operating member 64 has been sufficiently moved, the end portion of the spring or resilient member 60 engages the angular extension 42 of the slidably mounted member 40 and causes that member to slide relative to the lever arm 20 until the end portion 72 of the member becomes disengaged from the end of the thermostatic member 138. When disengagement is thus accomplished, the pivotally mounted subassembly is rotated by virtue of the urging force of the spring or resilient member 58 to a position such that the end portion 72 of the slidably mounted member 40 rests against the stop member 116. When the operating member 64 is then released, the urging force of the spring or resilient member 60 urges the shoulder 70 against the portion 42 of the slidably mounted member 40 so that the slidably mounted member is moved relative to the lever arm 20 and the portion 72 is extended beyond the end of the lever arm 20. The rotary motion of the pivotally mounted subassembly thus accomplished, causes the cam member 18 to engage the resilient contact carrying member 72 to open or disengage the contacts 88 and 90.

Since the current through the circuit controlled by the switch is caused to flow through the resistance coil or heating element 146, the heat produced in that coil or element is proportional to the current flow through the switch. Hence, in the event of an abnormal condition such as an excessive current flow through the switch, the thermostatic member 138 is caused to flex and to automatically be disengaged from the portion 72 of the slidably mounted member 40 to permit rotation of the pivotally mounted subassembly and disengagement of the contacts in a manner similar to that previously described.

An adjustment has been provided to permit regulation or adjustment of the flexure of the thermostatic member 138 necessary to effect release or disengagement of that member from the portion 72 of the slidably mounted member 40. An adjustment is also desirable to compensate for slight variations in the size of parts in manufacture. This adjustment is accomplished in the present switch through the mounting of the pivotally mounted subassembly on the adjustable pivotally mounted member 32. Movement or adjustment of the member 32 shifts the position of the pin or shaft 28 and hence the position of the pivotally mounted subassembly relative to the end of the thermostatic member 138 so that the portion 72 of the slidably mounted member 40 may be caused to engage the end of the thermostatic member to a greater or lesser degree. The thermostatic latch assembly comprises a unit that may be removed or replaced without disturbance to the rest of the switch structure. Since the thermostatic member 138 is exposed on more than one side to the resistance coil or heating element 146, and since the intervening heat transferring medium is air and a good conveyor of heat, the heat transfer efficiency of the assembly is high. That efficiency is also improved by

virtue of the thermostatic member 138 being disposed within the confines of the opening 126. The flexure of the thermostatic member 138 is substantially unrestrained because of the spacing of the other parts in the assembly therefrom. Although one form of the thermostatic latch assembly is disclosed it is to be understood that other forms might be used with this switch structure without departing from the spirit of the invention.

In the modification shown in Figs. 7 and 8 a compression spring is shown that performs substantially the same function as the spring or resilient member 60 previously described.

While the form of embodiment of the present invention as herein disclosed, constitutes a preferred form, it is to be understood that other forms might be adopted, all coming within the scope of the claims which follow.

What is claimed is as follows:

1. A switch, comprising in combination, an insulating mounting having an aperture therein, brackets secured to said mounting, a contact carrying member secured to said mounting, a resilient contact carrying member also secured to said mounting, said contact carrying members having contacts mounted thereon and in co-operative relation, said resilient contact carrying member being normally biased so as to cause said contacts to engage, a cam rotatably mounted on one of said brackets and located in position to engage said resilient contact carrying member, a lever arm secured to said cam and rotatably mounted therewith, a member slidably mounted on said lever arm and having an angularly projecting extension at one end, a resilient member urging said cam against said resilient contact carrying member and overcoming the said normal biasing force to separate said contacts, a thermostatic latch positioned to engage the slidably mounted member and hold said cam away from said resilient contact carrying member against the urging of said resilient member, a heating element associated with said thermostatic latch and electrically connected to one of said contacts which element if sufficiently heated causes said latch to flex and disengage said slidably mounted member to permit said resilient member to separate said contacts, and a manual operating member extending through the aperture in said mounting and engaging said angularly projecting extension for manually causing said slidably mounted member to engage said latch and for sliding said slidably mounted member to cause it to be disengaged from said latch.

2. A switch, comprising in combination, a mounting, brackets secured to said mounting, co-operating contacts, one of said contacts being fixedly mounted, means providing a resilient mounting for another of said contacts and normally biasing said contacts into engagement, cam means rotatably supported by one of said brackets, said cam being located in position to engage said resilient mounting means to disengage said contacts when said cam is rotated, a lever arm secured to said cam and rotatably mounted therewith, a member slidably mounted on said lever arm and having an angular extension at one end and normally projecting beyond said lever arm at its other end, a first resilient member tending to rotate said cam and lever arm about their pivotal mounting to force said contacts apart, a second resilient member urging said slidably mounted member to project beyond the end of said lever arm, a thermostatic latch for engaging the pro-

jecting end of said slidably mounted member to hold said cam in a position to permit said contacts to engage, said thermostatic latch flexing in response to temperature change to disengage 5 the end of said slidably mounted member, and an operating member engaging the angular extension of said slidably mounted member, said operating member providing means for manually engaging and disengaging the projecting end of 10 said slidably mounted member and said thermostatic latch to open and close said contacts.

3. A switch, comprising in combination, a mounting, brackets secured to said mounting, cooperating contacts, one of said contacts being 15 fixedly mounted, means providing a resilient mounting for another of said contacts and normally biasing said contacts into engagement, cam means rotatably supported by one of said brackets, said cam being located in position to engage said 20 resilient mounting means to disengage said contacts when said cam is rotated, a lever arm secured to said cam and rotatably mounted therewith, a member slidably mounted on said lever arm and having an angular extension at one end and normally 25 projecting beyond said lever arm at its other end, a first resilient member tending to rotate said cam and lever arm about their pivotal mounting to force said contacts apart, a second resilient member urging said slidably mounted 30 member to project beyond the end of said lever arm, a latch for engaging the projecting end of said slidably mounted member to hold said cam in a position to permit said contacts to engage, and an operating member engaging the angular extension 35 of said slidably mounted member, said operating member providing means for engaging and disengaging the projecting end of said slidably mounted member and said latch to open and close said contacts.

40 4. A switch, comprising in combination, a mounting, a bracket secured to said mounting, cooperating contacts normally biased into engagement, cam means rotatably supported by said bracket, said cam providing means for disengaging said contacts, a thermostatic latch member, said thermostatic latch member being adapted to flex in response to temperature change, spring urged extensible means rotatably supported with 45 and secured to said cam for engagement with said latch, resilient means for rotating said cam when said latch and extensible means become disengaged, and a linearly movable operating lever attached to said extensible means for effecting 50 manually the engagement and disengagement of said extensible means and thermostatic latch to cause engagement and disengagement of said contacts.

5. A switch, comprising in combination, a mounting, a bracket secured to said mounting, 55 cooperating contacts normally biased into engagement, cam means rotatably supported by said bracket, said cam providing means for disengaging said contacts, a latch member, spring urged extensible means rotatably supported with and secured to said cam for engagement with said latch, resilient means for rotating said cam when said latch and extensible means become disengaged, and a linearly movable operating lever attached to said extensible means for effecting 60 manually the engagement and disengagement of said extensible means and said latch to cause engagement and disengagement of said contacts.

6. In a switch, the combination comprising, 65 cooperating contacts, means normally biasing said contacts into engagement, a pivotally mounted

cam means for effecting engagement and disengagement of said contacts, a latch for engaging said cam means, a pivotally movable member supporting said pivotally mounted cam means for changing the position of the pivotal mounting of the pivotally mounted cam means and regulating the engagement of said cam means with said latch, and means for holding said pivotally movable member in a predetermined position.

7. In a switch for controlling an electrical circuit, the combination comprising, cooperating contacts, means for effecting engagement and disengagement of said contacts, said means being normally biased to disengage said contacts, a thermostatic latch adapted to flex in response to heat produced by current flow in said circuit, said thermostatic latch engaging said means when said contacts are engaged, means for adjusting the distance of flexure necessary to permit the release of said means, and manually operable means for actuating the means for effecting engagement and disengagement of the contacts.

8. In a switch, the combination comprising, cooperating contacts having an engaged and a disengaged position, means for effecting movement of said contacts to said positions, said means being normally biased to one of said positions, a thermostatic latch adapted to flex in response to temperature change, said thermostatic latch engaging said means to permit said contacts to remain in one of said positions against the normal biasing, and means for adjusting the distance of flexure necessary to permit the release of said means from said latch.

9. In a switch, the combination comprising, cooperating contacts having an engaged and a disengaged position, means for effecting movement of said contacts to said positions, said means being normally biased to one of said positions, a thermostatic latch adapted to flex in response to 110 temperature change, said thermostatic latch engaging said means to permit said contacts to remain in one of said positions against the normal biasing, means for adjusting the distance of flexure necessary to permit the release of said 115 means from said latch, and manually operable means for actuating the means for effecting movement of said contacts.

10. In a switch for controlling an electrical circuit, the combination comprising, cooperating 120 contacts having an engaged and a disengaged position, means for effecting movement of said contacts to said positions, said means being normally biased to one of said positions, a thermostatic latching means for engaging said means in one 125 of said positions and disengaging said means in response to temperature change and including, a thermostatic member that flexes due to temperature change, a block form having an opening therein for the accommodation of said thermostatic member, said member being secured at one end in said opening and having another end projecting therefrom, and a heating element in heat transferring relation with more than one side of said thermostatic latch and spaced therefrom and connected in series with said contacts 130 in said circuit.

11. In a switch for controlling an electrical circuit, the combination comprising, cooperating contacts having an engaged and a disengaged position, means for effecting movement of said contacts to said positions, said means being normally biased to one of said positions, a thermostatic latching means for engaging said means in one 145 of said positions and disengaging said means in 150

- response to temperature change and including, a thermostatic member that flexes due to temperature change, a block form having an opening therein for the accommodation of 5 said thermostatic member, said member being secured at one end in said opening and having another end projecting therefrom, and a heating element in heat transferring relation with more than one side of said thermostatic latch and spaced therefrom and connected 10 in series with said contacts in said circuit, said heating element offering substantially no restraint to the flexure of said thermostatic member.
- 15 12. In a switch, a thermostatic latch assembly, comprising in combination, a strip of insulating material having an opening therethrough, a heater coil wound on said strip so that the turns thereof cross said opening, a thermostatic latch member secured at one end to said strip and having a portion thereof surrounded by the turns of said coil, means for making connections to said coil, and means for mounting said strip on the switch.
- 20 13. In a switch, a thermostatic latch assembly, comprising in combination a thermostatic member, a block of insulating material having means 25 for the accommodation of the major portions of said thermostatic member within the confines of the planes defined by the outer surfaces of said block, said thermostatic member having one end secured to said block and the other end free to move in response to the flexing of said member, a heater coil wound on said block so as to surround a portion of said thermostatic member and so as to be spaced therefrom, means for making connections to said heater coil, and means for mounting said block. 80
14. In a heat responsive control assembly for a switch, the combination comprising, a thermostatic member, heat confining walls on more than one side of said thermostatic member, said walls being spaced from said thermostatic member, a heater element in heat transferring relation with more than one side of said thermostatic member only a single heat transferring medium intermediate said heater element and two sides of said thermostatic member to provide said heat transferring relation, and said medium offering substantially no impedance to the flexure of the thermostatic member, means for supporting said walls, and means for making electrical connection to said heater element. 85 90 95 100
